CHAIR OR THE LIKE

David Chapman, Chicago, Ill., and Richard G. Reineman,
Covina, Calif., assignors to Brunswick Corporation, a
corporation of Delaware

Filed Apr. 15, 1959, Ser. No. 55,512

Term of patent 14 years

(Cl. D15—1)

Fig. 1 is a perspective elevational view of the chair looking toward a front corner thereof, showing our new design;

Fig. 2 is a front elevational view of the chair;

Fig. 3 is a side elevational view of the chair looking toward the left-hand side thereof as viewed in Fig. 2;

Fig. 4 is a top plan view of the chair; and

Fig. 5 is a rear elevational view of the chair.

An essential characteristic of the chair design being the design of the chair seat and back including the flat seat having a down-turned front edge and down-turned side edge bead and the substantially flat back having the rearwardly turned side edges and top edge together with the opening in the back having a rearwardly extending lip and the contoured portion joining the seat and back, all as shown in the drawings.

We claim:

The ornamental design for a chair or the like, as shown and described.
